A. CODY.
DETACHABLE HOOK FASTENER.
APPLICATION FILED SEPT. 20, 1916.

Patented May 29, 1917.

FIG. 1.

FIG. 2.

UNITED STATES PATENT OFFICE.

ALICE CODY, OF NEWARK, OHIO.

DETACHABLE HOOK-FASTENER.

1,228,181.

Specification of Letters Patent.

Patented May 29, 1917.

Application filed September 20, 1916. Serial No. 121,192.

To all whom it may concern:

Be it known that I, ALICE CODY, a citizen of the United States, and resident of Newark, in the county of Licking and State of Ohio, have invented certain new and useful Improvements in Detachable Hook-Fasteners, of which the following is a specification.

The present invention relates to the class of buckles, buttons and clasps, and has particular reference to new and useful improvements in detachable hook fasteners, an object thereof being to provide a detachable hook fastener for association with a garment to detachably connect two parts thereof.

Another object of my invention is to provide a detachable hook fastener of the class described which is simple in construction, cheap to manufacture, neat in appearance and effective in operation.

A further object of my invention is to provide a detachable hook fastener of the class described which may be quickly and easily attached to any garment without the stitching ordinarily necessary.

A still further object of my invention is to provide a detachable hook fastener of the class described which when applied to a garment obviates the necessity of providing button-holes or the like.

Other objects and advantages to be derived from the use of my improved detachable hook fastener will appear from the following detailed description and the claims, taken with an inspection of the accompanying drawing, in which:

Figure 1 is a transverse sectional view of a detachable fastener embodying the improvements of my invention, the parts being shown unhooked; and

Fig. 2 is a disassembled perspective view of the various parts of the fastener.

Referring more particularly to the drawing, wherein similar characters of reference designate like and corresponding parts throughout the various views, 1 and 2 designate the portions of a garment to be connected, such as the free edges of the front of a coat or the like, A and B designate in their entireties the two main portions of my improved detachable fastener.

Referring to the section A, I provide a body 3 having an enlargement 4 on which 55 may be placed any design. A threaded

shank 5 extends from the central portion of the body 3 through the portion 1 of the garment and engages with the central portion of a disk 6, said disk being provided with an enlargement 7 to accommodate said threaded shank. The marginal edges of the disk 6 are rolled to provide an annular flange 8 which is in engagement with a plate 9, said plate having a T shaped aperture 10 therein, the radial leg 11 of said aperture terminating approximately at the central portion of said plate. A prong 12 extends from the body 3 of the portion 1 of the garment to prevent the body from rotating thereon.

Referring specifically to the section B, I provide a pair of plates 13 and 14, the plate 13 having a threaded shank 15 for engagement in an enlargement 16 formed on the plate 14, said shank and enlargement passing through the portion 2 of the garment. A prong 17 formed on the plate 13 prevents rotation of said plate relative the garment. A hook is provided on the plate 13, said hook having an elongated head 18 directed to engage in the leg 11 of the recess.

When the parts A and B of my improved fastener are applied as shown to the portions 1 and 2 of the garment and the hook 18 engaged with the recess 11 accidental disconnection of the portions of the fastener is practically impossible. It will be readily apparent that stitching of the garment and the provision of button-holes is unnecessary when the device of my invention is employed, the garment merely being perforated to accommodate the threaded shank of the two sections of the device. The prongs themselves will prevent rotation of the element and will also serve as an additional securing means therefor. The device may be cheaply manufactured, and consists of very few parts, particular attention being directed to the facility with which the hook may be engaged with the recess.

From the above description taken in connection with the accompanying drawing, it is thought that a clear and comprehensive understanding of the construction, operation and advantages of my invention may be had, and while I have shown and described the device as embodying a specific structure, I desire that it be understood

that such changes may be made in said structure, as do not depart from the spirit and scope of the invention as claimed.

Having thus fully described my invention, what I claim as new and desire to secure by Letters Patent, is:—

1. The combination with a garment having overlapping portions, of a hollow head secured to the inner side of one of said portions, said head having a flat under side with a T-shaped opening therein, a plate secured to the opposite garment portion, and a hook member on said plate having a flat bill portion disposed substantially parallel with the plate and adapted to be positioned through the shank portion of the T-shaped opening in the head and the shank of said hook being adapted to slide longitudinally in the head of the opening upon transverse movement whereby the bill will surely fasten the garment portion.

2. A detachable fastener of the class de-

scribed comprising a body having a shank extending therefrom, a hollow head consisting of a disk and plate, said disk having the peripheral edge therefor rolled to engage said plate, said shank being adapted to engage said hollow head through a portion of the garment, said plate being provided with a T-shaped opening, a pair of circular plates one having a threaded shank and the other an enlargement adapted for relative engagement, means to prevent rotation of said plates relative to a portion of the garment to which the same is adapted to be secured, a hook carried by one of the plates having a bill portion adapted to pass through the shank of the T-shaped opening and the shank of said hook being adapted to slide longitudinally in the head portion of said opening for the purpose specified.

In testimony whereof, I affix my signature hereto.

MRS. ALICE CODY.
